Inventor
Nevvens N. Nunn

UNITED STATES PATENT OFFICE.

NEVVENS N. NUNN, OF MAPLEWOOD, MISSOURI, ASSIGNOR TO THE ALMETAL MANUFACTURING COMPANY, OF MAPLEWOOD, MISSOURI, A CORPORATION OF MISSOURI.

WASHING-MACHINE.

1,275,729.

Specification of Letters Patent.

Patented Aug. 13, 1918.

Application filed February 21, 1917. Serial No. 150,062.

To all whom it may concern:

Be it known that I, NEVVENS N. NUNN, a citizen of the United States, residing at Maplewood, St. Louis county, Missouri, have invented a certain new and useful Improvement in Washing-Machines, of which the following is a full, clear, and exact description, such as will enable others skilled in the art to which it appertains to make and use the same, reference being had to the accompanying drawings, forming part of this specification.

My invention relates to washing machines, the principal object of my invention being to provide a clothes container which has connections with the hinged lid or cover of the machine so that said container will be raised and lowered as the lid or cover of the machine is opened and closed.

20 Further objects of my invention are, to provide a clothes container with a reticulated bottom whereby the wet clothes may readily drain when the container occupies an elevated position, and further, to loosely mount the container on its supports, thereby permitting said container to be readily removed from the machine whenever desired.

With the foregoing and other objects in view, my invention consists in certain novel features of construction and arrangement of parts hereinafter more fully described and claimed and illustrated in the accompanying drawings, in which—

35 Figure 1 is a plan view of a washing machine provided with a clothes container of my improved construction;

Fig. 2 is a vertical section taken through the center of the tub or receptacle of the 40 washing machine and showing my improved clothes container positioned therein;

Fig. 3 is an enlarged vertical section taken approximately on the line 3—3 of Fig. 2;

Fig. 4 is an enlarged vertical section taken 45 on the line 4—4 of Fig. 1.

Referring by numerals to the accompanying drawings, 12 designates tubular posts or uprights which are suitably framed together and which serve to support the receptacle forming the body of my improved washing machine.

Secured in any suitable manner to these posts or uprights is a plate 13 provided with an opening 15 which is adapted to be occupied by a burner (not shown) for oil or

gaseous fuel and positioned upon plate 13 and supported thereby is a receptacle 18, preferably constructed of sheet metal and which forms the main body of the washing machine.

Rigidly fixed in any suitable manner to the top of the receptacle 18 is a ring 19 and formed integral therewith are outwardly projecting ears 20 from which depend integral pins 21, the latter being seated in the upper ends of the tubular posts or standards 12. (See Fig. 4). This construction provides a very strong and substantial support for the receptacle 18 and the same is maintained in a comparatively rigid manner during the washing operations.

Formed integral with the ring 19 is an inwardly projecting flange 22 and formed integral with one side of said ring and flush 75 with the top thereof is a horizontally disposed plate 23, the top of which is provided with a series of integral lugs 24.

A cover plate 25 is hinged to the lugs 24, the edge of said plate resting upon ring 19 80 and formed integral with this plate near its edge is a depending flange 26 which is adapted to fit snugly within the ring 19 and rest upon the flange 22 when said cover plate is closed.

Arranged within the container 18 is a pair of oppositely arranged vertically disposed channel shaped guides 27 in each of which is arranged for vertical movement a substantially L-shaped hook 28. These 90 hooks are connected to the lower ends of chains or cables 29, the latter extending upward alongside of grooved pulleys 30, the latter being journaled in suitable bearings on ring 19 and the upper ends of said 95 chains or cables are secured to cover plate 25.

Resting upon the oppositely disposed pair of hooks 28 is a clothes support or holder, the same comprising a ring 31 to the bottom of which is fixed a section 32 of reticulated material, preferably wire netting.

Normally, or when cover plate 25 is in closed position, this clothes support or container occupies a position near the bottom of 105 container 18 and when the cover plate is swung upward into open position, said clothes holder or container is elevated to the position shown by dotted lines in Fig. 4.

To open the tub or container for the pur- 110

pose of removing the clothes after washing operations, cover plate 25 is swung upward and outward into the positions shown by dotted lines in Fig. 2, such movement drawing the chains 29 upward over pulleys 30 and consequently elevating the clothes container comprising the parts 31 and 32. When the container is thus elevated, the clothes may readily drain and are in a position where they may be readily engaged to be delivered to the wringer or to the rinsing water located in another tub or container.

In the event that it is desired to entirely remove the clothes holder from the receptacle 18, said holder can be easily elevated from the L-shaped hooks 28 and withdrawn from the upper end of the receptacle. The ring 19 materially strengthens and reinforces the upper end of the receptacle 18 and as the tubular legs or supports 12 directly engage the pins 21, depending from said ring 19, the receptacle and parts carried thereby are maintained in a rigid and substantial manner, particularly while the washing operations are being performed.

It will be readily understood that minor changes in the size, form and construction of the various parts of my improved washing machine can be made and substituted for those herein shown and described, without departing from the spirit of my invention, the scope of which is set forth in the appended claims.

35 I claim:

1. In a washing machine, a container, a ring secured to the upper end thereof, a

plate formed integral with said ring at one side thereof, a cover hinged to said plate, a clothes receptacle arranged to move vertically within the container, flexible connections secured to the hinged cover and extending downwardly into the container, and L-shaped members secured to the lower ends of said flexible connections, which L-shaped members engage beneath the clothes receptacle.

2. In a washing machine, a container, a hinged cover therefor, a clothes carrier arranged for vertical movement within said container, guides on opposite sides of the container, an L-shaped member mounted for sliding movement in each of said guides, which L-shaped members engage the clothes carrier, and flexible connections from said members to the hinged cover plate.

3. In a washing machine, a container, a hinged cover plate therefor, a clothes carrier arranged for vertical movement within the container, L-shaped hooks adapted to engage said clothes carrier, pulleys secured to the upper portion of the container on opposite sides thereof, and flexible members secured to the hooks and to the hinged cover plate, which flexible connections pass over the pulleys.

In testimony whereof I hereunto affix my signature, in the presence of two witnesses, this 12th day of February, 1917.

NEVVENS N. NUNN.
